The ornamental design for a display screen with graphical user interface, as shown and described.

DESCRIPTION

FIG. 1 is a front view of a display screen with graphical user interface, showing our new design; and,

FIG. 2 is a front view of the display screen with graphical user interface of FIG. 1, in which a mobile terminal in broken lines is provided to illustrate an example environment.

The broken line drawing of the mobile terminal, and the text/words, numbers, symbols and otherwise images shown in broken lines in FIGS. 1 and 2 are for illustrative purposes only and form no part of the claimed design.
